NECKWEAR ACCESSORY

Henry E. Lane, New York, N. Y.

Application October 21, 1946, Serial No. 704,751

3 Claims. (Cl. 24—49)

1

The present invention relates to a neckwear accessory and it particularly relates to a device for use by men in connection with maintaining their four-in-hand ties or both their four-in-hand ties and collars in dressed condition.

Four-in-hand ties tend to slip out of position or become loose or shift to the side, even though they may be most carefully adjusted by the wearer thereof and it is among the objects of the present invention to provide a simple, inexpensive, durable, light-weight, readily manufactured and merchandised accessory which may be employed to hold four-in-hand ties in initially adjusted or dressed position without slippage, loosening and offsetting during course of a working day or during the course of an evening's activities which will eliminate the necessity of constant adjustment, fingering and tightening of such ties during the day or evening.

Another object is to provide a simple, readily manipulated male tie and collar accessory which will without injury to or cutting of tie and collar both hold a collar in shape and prevent a tie knot from slipping or loosening or becoming offset.

A further object is to provide an ornamental and distinctive collar holder which will also enable holding of the tie knot in final adjusted position with respect to said tie.

Still further objects and advantages will appear in the more detailed description set forth below, it being understood, however, that this more detailed description is given by way of illustration and explanation only and not by way of limitation, since various changes therein may be made by those skilled in the art without departing from the scope and spirit of the present invention.

In accomplishing the above objects, it has been found most satisfactory to form a clip device having thin elongated pin or dagger elements which may be readily inserted into the knot of a four-in-hand tie in such manner as not to be visible or to be concealed by the knot.

The device may take the form of a U-shaped wire device, the ends of the legs are sharpened and turned inwardly to form overlapping pins to be inserted into the sides of the four-in-hand knot with the base of the U concealed behind the knot. The base of the U may also take the form of a coil spring. The pins or sharpened ends of the legs when inserted into the sides of the knot will hold the same in position preventing slippage, loosening or offsetting.

If desired, the pin inserts may be carried by a collar holder or fastener. The rear of the collar clip or holder may be recessed to receive the tie knot and the front elements for clipping the side edges of the collar opening may be terminated short of said recess so that the tie knot will rest therebetween.

2

The front elements of the collar holder or clip are desirably formed of short tubes which carry sliding pin members having offset cam elements or knobs which may be used as handles to press the pin through the tie knot and then turned to grip the collar edge and hold the accessory in position.

Usually the sliding pin is only provided on one side so that the other side of the collar clip may be held in position clipped or fastened to the collar edge. However, usually the collar clip portions or knobs may be permanently mounted on said tubular elements with a sliding pin being provided for engaging the tie knot and having an end knot or handle member which does not engage the collar. In this construction since the clip may be fixed in position on the collar before engagement with the knot, two sliding pins may be used one on each side.

20 The pins may conveniently be held in adjusted position by frictional grip with the tubular guides, which friction may be increased by providing a bow in the portion of the pin which stays in the tubular receiver after final adjustment.

25 In the drawings which show several embodiments of the invention by way of illustration and not by way of limitation,

Fig. 1 is a front elevational view of a collar and four-in-hand tie combination with the collar and tie accessory in position thereon,

30 Fig. 2 is a top separated view of the accessory of the present invention with the knot engaging element removed from the collar engaging element upon an enlarged scale as compared to Fig. 1,

35 Fig. 3 is a horizontal sectional view taken from the line 3—3 of Fig. 1 upon an enlarged scale as compared to Fig. 1 showing the accessory in position on a collar and attached to a four-in-hand knot,

40 Fig. 4 is a horizontal sectional view similar to Fig. 3 of an alternative form of accessory with the collar and knot engaging elements in position on a collar and engaging a tie knot.

45 Fig. 5 is a side elevational view upon an enlarged scale of an attachment enabling change in color of the collar engaging knobs of the collar attachment.

Fig. 6 is a top plan view upon an enlarged scale of another type of accessory designed to engage the knot of a four-in-hand tie alone.

50 Fig. 7 is a top plan view similar to Fig. 6 of another form of accessory also designed only to engage the knot of a four-in-hand tie alone.

55 Fig. 8 is a back elevational view taken from between the tie and shirt looking forwardly at the back of the knot showing the device of Fig. 6, upon a reduced scale as compared to Fig. 6, in position thereon holding the knot in position,

60 Fig. 9 is a horizontal sectional view similar to,

but upon a reduced scale as compared to Figs. 3 and 5, showing still another form of the invention with two sliding knot engaging elements designed to engage a knot in position on a collar.

Referring to Figs. 1 to 3, the collar A of the men's shirt has the adjacent edges 10 which are engaged by the collar clasp or accessory B. The four-in-hand tie C has been tied into a knot 11 with the depending portions 12 and is engaged by the elongated sliding pin D serving as a knot engaging element.

As shown in Figs. 2 and 3 the accessory B has a back or rear element 13 to fit behind the collar A, which element 13 is rearwardly bowed or depressed at 14 to receive the knot 11 of the tie C.

Mounted on the back element 13 at 15 and 16 are the legs 17 and 18 which extend upwardly and carry the small tubular elements 19 and 20.

The formation of a recess E by the depression 14 and between the legs 17 and 18 without extending the elements 19 and 20 straight across the front of the accessory B is also a feature of the present invention.

As shown the pin element D has an offcenter knob or handle 21 which may be of metal, glass or plastic colored to match the shirt or tie. The pin or shank 22 has a sharp point 23 and is curved to fit the curve of the tubular guides 19 and 20.

The knob end 24 is permanently attached to the end 25 of the tubular guide 19 in the form shown in Fig. 2, but it may take the form E shown in Fig. 5 where it is removable and replaceable to give different colors or permit different types of jewels or objects to be employed whether of metal, plastic, gems or glass. The object 26 in Fig. 5 as shown is provided with an attachment 27 to be inserted in the end 25 of the tube 19. The attachment 27 is shown as consisting of two spring apart wires but it may also be a conical plug or other gripping device.

In operation the tie C is tied with knot 11. Then the pin D is withdrawn and the collar edge 10 is gripped as shown at left of Fig. 3 below knob 24. Then the pin 22 is inserted into the tube 20, through the knot 11 and into the tube 19 and the knob 21 is then turned slightly so that it will grip the edge 10 of the collar A below the knot 21. The offset position of the knob 21 will give it a camming action. The curvature of the shank 22 will permit sufficient camming of the knob 21 tightly to grip the collar edge 10.

In Fig. 4 the clip B and pin D are of the same construction as in Figs. 1 to 3 except that the bow 28 aids in frictionally holding the pin D in the sleeve or cylindrical guide 20.

In Fig. 6 the clip F has inturned overlapping sharpened ends 29 and 30, side legs 31 and 32 and a curved base 33. Upon attachment, the ends 29 and 30 as shown in Fig. 8 will extend into the sides of the knot 11 and the bow 33 will be in the back of the knot 11 where it will not be seen. The pin ends 29 and 30 will project through the knot 11 and prevent the layers of fabric from moving in respect to each other.

In the embodiment G of Fig. 7 the pin ends 34 and 35 overlap and function like the pin ends 29 and 30 in Fig. 6. The legs 36 and 37 carry the pin ends 34 and 35 respectively and are connected by a coil spring 39. The device G is used in the same manner as the device F of Fig. 6.

In the device H of Fig. 9 the tubes 44 and 45 are both provided with sliding pin members J and K, with knobs 40 and 41 and shanks 42 and 75

43. The tubes 44 and 45 have presser feet 50 and are opened at both ends. The sharpened ends 46 and 47 will overlap at 48 when inserted into a tie knot.

5 The sharpened points 23, 29, 30, 34, 35, 46 and 47 are desirably of such thinness as not to damage the fabric of the tie C when inserted into the knot 11 thereof. At the same time they will prevent the fabric layers of the knot 11 from loosening, slipping or offsetting.

10 In Fig. 2 the knob 24 pressing the collar edge 10 against the back 13 will hold the device B in position when the pin D is inserted through the knot 11. In Fig. 9 this will be done by the presser feet or knobs 50.

15 The present invention is not only applicable to the tie known as four-in-hand, but also to any type of men's neckwear, including any type of tie having a knotted structure adjacent or at the break in a collar.

20 Instead of the recess E and curve 14, the front of the collar clip might follow the usual curve.

25 As many changes could be made in the above neckwear accessories and many apparently widely different embodiments of this invention could be made without departing from the scope of the claims, it is intended that all matter contained in the above description or shown in the accompanying drawings shall be interpreted as illustrative and not in a limiting sense.

30 What is claimed is:

1. A men's clothing accessory comprising a laterally elongated metal base member to extend beyond and in back of the adjacent edges of the collar, pin guide members positioned in front of said metal base member provided with legs on the inside ends thereof to mount said tubular members on said base member adjacent the edges of said collar and to leave a substantial space between the adjacent ends of said tubular members for reception of the knot of a tie, depending members at the outer ends of said tubular members to press down upon the outer faces of the edges of the collar and clamp said edges against said metal base, and elongated pin means inserted into said tubular members having enlarged heads to be stopped against the outer ends of said tubular members, the inner ends of said pins to penetrate into the knot of a tie in the space between the inner ends of said tubes.

40 2. The accessory of claim 1 in which the base has a recess for receiving the knot of the tie between said legs.

45 3. The accessory of claim 1 in which the pointed ends of said elongated pins cross and contact each other in the space between the inner ends of said tubular members.
